UNITED STATES PATENT OFFICE.

ALONZO C. MATHER, OF CHICAGO, ILLINOIS.

CAR ROOF.

Application filed November 28, 1924. Serial No. 752,531.

My invention relates to improvements in car roofs designed to be used on steel constructed cars but may be used for other purposes, and the objects of my improvements are, first, to provide a metal roof which is to a degree flexible; second, to have the parts of the roof laid together without being soldered or otherwise rigidly secured together; third, to make a roof which is easily repaired in sections; forth, to make a roof which is absolutely waterproof; fifth, to make a roof which is applicable to the present standard construction of cars; sixth, to make a roof which is novel, cheap and durable, and other features to become apparent from the construction to follow.

In the construction of railroad car roofs which are made of sheet metal it is desirable to have a certain amount of looseness or flexibility between the pieces of sheet metal so that the slight twisting or shifting of the car frame will not open the joints between the pieces of sheet metal or otherwise cause the roof to become leaky; it is also desirable to have the construction such that it can be easily repaired; to have the roof waterproof; to have the roof applicable to the standard make of cars and to have it light and durable, and all these desirable features are attained by the use of my invention which comprises a plurality of troughs spaced apart extending from one side of the car across the apex of the roof to the other side of the car and long strips of sheet metal also extending from one side of the car to the other with their bent down edges extending into the said troughs.

To describe my invention so that others versed in the art to which it pertains can make and use the same, I have illustrated it on the accompanying four sheets of drawings forming a part of this specification, and in which:

Figure 1, is a plan view of a car roof embodying my invention foreshortened and partly broken away for purposes of illustration; Fig. 2, is a side elevation of a car roof end or diaphragm forming a part of my improved roof; Fig. 3, is a cross sectional view on line 3—3 of Fig. 2, viewed in the direction indicated by the arrows; Fig. 4, is a side elevation of a U shaped trough forming a part of my invention; Fig. 5, is a cross sectional view taken on line 5—5 of Fig. 4, viewed in the direction indicated by the arrows; Fig. 6, is a cross section taken on

line 6—6 of Fig. 1, viewed in the direction indicated by the arrows; Fig. 7, is a section taken on line 7—7 of Fig. 1, viewed in the direction indicated by the arrows; Fig. 8, is a sectional view taken on line 8—8 of Fig. 1, viewed in the direction indicated by the arrows; Fig. 9, is a sectional view taken on line 9—9 of Fig. 1, viewed in the direction indicated by the arrows; Fig. 10, is an inverted plan view of a fractional part of the roof at one of the several U shaped troughs or ribs, enlarged and partly broken away for purposes of illustration; Fig. 11, is a sectional view taken on line 11—11 of Fig. 10, viewed in the direction indicated by the arrows; Fig. 12, is a similar view to Fig. 10, showing a rib next to the end of the car roof; Fig. 13, is a sectional view taken on line 13—13 of Fig. 12, viewed in the direction indicated by the arrows; Fig. 14, is a sectional view taken on line 14—14 of Fig. 1, showing how the running boards are secured to the roof; Fig. 15, is a sectional view taken on line 15—15 of Fig. 1, viewed in the direction indicated by the arrows showing the roof resting on the upper frame of the car and the manner of fastening the same thereto; Fig. 16, is a side elevation of the center roof supporting angle foreshortened; Fig. 17, is a similar view of one roof side supporting Z bars; Fig. 18, is a detail sectional view showing how the roof cross ribs fit into notches provided in the center roof supporting angle; Fig. 19, is a similar view of one side roof supporting Z bar; Fig. 20, is a perspective view of one roof sheet metal plate; Fig. 21, is a perspective view of a roof supporting cross rib; Fig. 22, is a perspective view of a roof supporting brace, and Fig. 23, is a sectional view taken on line 23—23 of Fig. 15, showing the connection between the roof cross rib and the supporting Z bar.

Similar reference characters refer to similar parts throughout the several views.

The roof supporting framework comprises ends or diaphragms 25, side Z bars 26 and a central supporting angle 27. The Z bars 26 are cut away at their ends as seen at 28 in Fig. 17, and are riveted to the diaphragms 25 as seen in Fig. 9, and the angle 27 has its ends riveted to the diaphragms 25 as seen in Figs. 6 and 8, by means of interposing a short piece of I beam 29. This arrangement permits of very light construction and yet sufficiently strong to serve the purpose. The end diaphragms 25 rest on

the channels 30 forming the top sills of the car ends, and the Z bars 26 rest on the angles 31 forming the top sills of the sides of the car, see Figs. 1, 6, 7, 8, 9 and 15.

5 The Z bars 26 and the angle 27 have their upper edge provided with spaced rectangular notches 32 to receive the U-shaped troughs 33 which extend from one side Z bar to the other side Z bar and have their ends 10 projecting out a short distance beyond the Z bars, so that water passing down in the troughs will be delivered beyond the side of the car body.

As clearly shown in Figs. 1, 16 and 17, 15 the notches 32 are equally spaced throughout the length of the roof from one car end to the other car end, so that the sheet metal strips 34 are all of the same width when in proper position having their bent down 20 edges 35 extending into the troughs 33. To strengthen and support the roof sheets 34 I preferably arrange six rows of braces 36 under the sheets 34 and spanning the spaces between the troughs 33 with their bent down 25 ends 37 extending into the troughs. To lock the sheets 34 and the braces 36 to the troughs 33, cotter pins 38 are passed through registering perforations in the several parts as clearly shown in Figs. 10 to 13. As will be 30 seen in Figs. 12 and 13, the end troughs 33 are riveted to the end diaphragms 25. As shown in Figs. 6, 7, 15 and 23, the troughs 33 near their ends are secured to the Z bars 26 and the angles 31 by means of bolts 39,

the heads of which fit snugly in the troughs 35 to prevent the same from turning, and the nuts 40 below the angles 31 are provided with nut locks 41 to prevent the nuts turning loose.

The running boards 42 are secured by 40 screws to the saddles 43 which are secured to the central part of the roof by means of the Z shaped metal straps 44 which are bolted at their upper ends to the saddle and have their lower ends extending into the troughs 45 33 where they are secured by the cotter pins 38.

The customary ladder round is shown at 45 and the usual brake wheel is shown at 46.

Having thus fully described my invention 50 what I claim as new and desire to secure by Letters Patent of the United States is:—

In a car roof in combination, carlines, pur- 55 lines extending between the carlines, roof sheets supported upon said carlines and pur- lines, said carlines being U-shaped in sec- tion and having laterally extending flanges at their upper edges, said purlines and said roof sheets being supported on said later- 60 ally extending flanges and each having depending flanges at opposite edges thereof extending into said carlines and means se- curing the depending flanges of the said pur- lines and roof sheets to the carlines.

In testimony whereof I have signed my 65 name to this specification this 18th day of October, 1924, at Chicago, Illinois.

ALONZO C. MATHER.
